FORREST E. BINGHAM AND THOMAS TOMLINSON, OF NEW BEDFORD, MASSACHUSETTS.

SPOOLING-MACHINE TENSION DEVICE

1,408,560.

Specification of Letters Patent.

Patented Mar. 7, 1922.

Application filed May 12, 1921. Serial No. 469,013.

To all whom it may concern:

Be it known that we, FORREST E. BINGHAM and THOMAS TOMLINSON, citizens of the United States, residing at New Bedford, 5 in the county of Bristol and State of Massachusetts, have invented certain new and useful Improvements in Spooling-Machine Tension Devices, of which the following is a specification.

10 This invention relates to certain new and useful improvements in tension devices for spooling machines, and the primary object thereof is to provide a tension device which utilizes a freely mounted weighted element, 15 such as a ball, which functions to tension the thread by bearing thereon, and a device in which balls of varying sizes or weights can be easily and quickly substituted in order to vary the tension exerted 20 thereby on the thread.

A further object of the invention is to provide a device of this kind that is formed to free itself of the accumulation of any foreign matter, such as waste, fly or dirt.

25 The invention further aims to provide a device of this type which is of simple and economical construction and which is devoid of any moving parts which require lubrication.

30 Further and other objects will be later set forth and manifested in the course of the following specification.

In the drawings:

Figure 1, is a side elevation of the invention applied to a spooling machine;

Figure 2, is an enlarged side elevation of the invention;

Figure 3, is a top plan view, and

Figure 4, is a section on line 4—4 of

40 Figure 3 illustrating in dotted lines the use of balls of varying diameters.

In proceeding in accordance with the present invention, a body is employed which has a forked end 2 equipped with a set screw 3, to receive and be clamped onto a rod A, of the spooling machine, which rod has vertical rising and falling movements and is interposed as usual between the cop B and the spool C. At its outer or free portion, 45 the body is formed with an offset 4 which is formed with a deep conical shaped cup 5, the interior walls of which are formed 50 perfectly straight, the cup having an open top and an open bottom, the latter of sufficient size so as to allow any fly, dirt or

waste to freely gravitate therethrough to thus maintain the cup in a clean condition. The outer side of the cup is formed with a longitudinal slot 6 which extends through the top and bottom thereof, and is further 60 formed with a pair of guide arms or fingers 7 and 8 that flank the slot 6. The arm 7 is straight, while the arm 8 is preferably curved outwardly away from the arm 7 to thus form an outwardly flaring mouth for 65 the slot 6 and allow of the thread being more easily introduced into the slot and therethrough the cup interior.

Freely mounted within the cup interior is a ball 9 of suitable weight and diameter 70 and which, through the action of gravity, bears on and holds the thread T, in frictional engagement with the interior wall of the cup. Obviously balls of various weights and diameters can be easily substituted by merely lifting same out of and dropping them into the cup.

In threading the device, the thread is simply passed between the arms 7 and 8, and when it begins to move it will draw 80 itself under the ball. Consequently, it is unnecessary to remove the ball when it is desired to thread the device.

The device can be made of cast metal and thus can be economically produced and by 85 virtue of the screw, the body may be adjusted with respect to the rod A so that the thread will engage the cup interior throughout the depth thereof to thus effect uniform draw on the thread.

The cup is made deep and flared to a degree to allow balls of varying diameters to be used and still not move out of the cup as shown in Figure 4.

What is claimed is

1. In a tension device for spooling machines, a body having a forked end provided with a set screw for adjustable attachment to the vertically rising and falling rod of a spooling machine, said body being formed 100 with an offset adjacent its outer end portion, said offset being provided with a cup of conical interior form, said cup having an open top and bottom and having a longitudinal slot on its outer side and having 105 a pair of arms extending outwardly therefrom and arranged on opposite sides of the slot, one of the arms being curved outwardly to form a flaring mouth formation leading into the slot, and a ball freely placed in 110

the cup to engage the thread and hold same against the wall of the cup opposite to the slot.

2. In a tension device for spooling machines, a body, means on one end of the body to secure same to the machine, an offset on the opposite end of the body having a cup of conical interior form, the cup being held by the offset to one side of the body so that the thread will pass along a side of the body without engaging the same, the cup having a thread inlet, and a ball loosely placed in the cup.

3. In a tension device for spooling machines, a body having one end formed to engage about the falling and rising rod of

the spooling machine, means to adjustably secure said end to the rod so as to enable the body to be pivoted about the rod and then rigidly affixed thereto, an offset on the 20 opposite end of the body having a cup of conical interior form, the cup being held by the offset to one side of the body so that the thread will pass along a side of the body without engaging the same, the cup having 25 a thread inlet, and a ball loosely placed in the cup.

In testimony whereof we affix our signatures.

FORREST E. BINGHAM.
THOMAS TOMLINSON.
